MACHINE FOR RESAWING SLABS

Edward E. Marshall and Chester B. Zumwalt,
Oakland, Calif.

Application June 6, 1939, Serial No. 277,668

9 Claims. (Cl. 143—5)

This invention relates to machines for sawing split cedar slabs to provide a type of shake having a split surface on one side and a sawed surface on the other side.

Shakes of this type are commonly called re-sawed shakes and will be hereinafter so referred to. Re-sawed shakes are in demand for certain uses because they have one split surface which may be turned outwardly to give the desirable appearance and weathering qualities of a shake and one sawed surface which will fit smoothly and firmly against sheeting or like sawed lumber to which the shake is applied.

Re-sawed shakes are made from split cedar slabs which are usually from 32" to 38" long, vary from 1½" to 2" thick, are of substantially the same thickness at the two ends and have two split faces. Two re-sawed shakes are made from each of these slabs by sawing the slab longitudinally in a plane slightly inclined relative to the two faces of the slab or relative to the medial plane of the slab to cut each slab into two tapered shakes each shake having a thin tip and a thicker butt and each shape having one split surface and one sawed surface.

An object of this invention is to provide an improved machine of simple and efficient construction for re-sawing split cedar slabs rapidly and accurately and inexpensively to form tapered shakes.

Another object of this invention is to provide a machine of this nature having readily adjustable means by which the operator can vary the thickness of the tip of one of the shakes cut from each slab to secure a thin tip and yet avoid feathering the tip by cutting into the face grooves adjacent the tip, the adjustment being made to suit the individual requirements of each slab without stopping the machine and without reducing the speed at which the shakes are fed and sawed.

Another object is to provide a machine of this nature in which the danger of injuring the operator is reduced to a minimum as the machine feeds the slab to the saw without requiring the hands to be used near the saw.

Other and more specific objects of the invention will be apparent from the following description taken in connection with the accompanying drawings.

In the drawings, Fig. 1 is a plan view of a machine constructed in accordance with this invention, parts being broken away.

Fig. 2 is an end elevation of the same taken substantially on broken line 2—2 of Fig. 1.

Fig. 3 is a sectional view taken substantially on broken line 3—3 of Fig. 1, parts being broken away.

Fig. 4 is a fragmentary sectional view similar to Fig. 3, showing certain parts in a different position.

Fig. 5 is a fragmentary sectional view on a larger scale than Fig. 1, taken substantially on broken line 5—5 of Fig. 1.

Fig. 6 is a fragmentary sectional view of a modified form of slab support which may be used in connection with this invention.

Fig. 7 is an edge view of a cedar slab of the type this machine is adapted to re-saw.

Figs. 8 and 9 are fragmentary perspective views of the two end portions respectively of a cedar slab.

Like reference numerals designate like parts throughout the several views.

The frame of the machine comprises upright supports or legs 10, horizontal frame bars 11 and a top plate or table 12. Two transverse shafts 13 and 14 are positioned at the respective ends of the frame and journaled in bearings 15 supported by frame bars 11. Two spaced apart sprocket wheels 16 are secured to each shaft 13 and 14 and two endless link belts 17 are operatively disposed on the sprocket wheels 16. The upper lap or portion of each link belt rests on the table 12 throughout the greater portion of its length.

Transverse slab supports 18 and 19 extend crosswise between the two link belts like slats and are fixedly secured at their ends to the respective link belts. The slab supports 18, see Figs. 1, 3 and 7, are L shape in cross section and are adapted to receive the rear end portions of cedar slabs 20. The slab supports 19 are preferably flat or rounded in cross section and are adapted to support the forward end portions of cedar slabs 20. One slab support 18 and one slab support 19 constitute a pair. The two supports of each pair are spaced just far enough apart to receive slabs of predetermined length and several pairs of such supports are provided on the link belts 17. The distance between adjacent pairs of supports 18 and 19 may vary. Different interchangeable pairs of belts may be provided for use with slabs of different length. In practice it is desirable to provide for the handling of slabs of 32", 34" and 36" length but obviously any desired number of length variations may be taken care of in this manner.

A band saw 21 extends crosswise of the table 12, at substantially right angles to the link belts

17 with the lower lap thereof positioned a short distance above the path of travel of the uppermost portions of the supports 19 and the teeth of the saw turned so that the slabs will be moved into engagement with said teeth by movement of the link belts 17 in the direction indicated by the arrows in Fig. 1. The endless band saw 21 is mounted on pulleys or wheels 22 that are supported in bearings 23 in cross bars 24. Preferably the bearings 23 for at least one of the wheels 22 are adjustable by screws 25 or equivalent means to maintain a proper tension on the band saw. One of the band saw wheels 22 is power driven in any suitable manner, such as by a motor 26 connected by a belt 27 with a sheave 28 on the shaft 29 of said band saw wheel. The shaft 14, that carries one set of sprocket wheels 16 on which the link belts 17 are disposed, is preferably driven from the same motor by means which synchronizes the drive of the saw and the drive of the link belts. The driving means for shaft 14, herein illustrated, comprises a worm wheel 30 on shaft 14 engaged by a worm 31 on a shaft 32. The shaft 32 is journaled in a bracket 33 and has a sheave 34 connected by a belt 35 with a sheave 36 on the saw wheel shaft 29.

A hold down roll 37 is adapted to rest upon the slab 20 which is being re-sawed. This hold down roll 37 is operatively mounted in frame means 38. The frame means 38 is connected by pivots 39 to frame brackets 40. This allows the roll 37 to move up and down freely. The weight of the roll 37 rests on the slab 20 and tends to hold the slab down. A stop member 41 on the frame means 38 is positioned so as to engage with a guide rail 42 to limit the downward movement of the roll 37. The guide rail 42 extends longitudinally of the frame above the link belt 17 shown at the left in Figs. 1 and 2. Brackets 43 support the guide rail 42.

Means are provided for adjusting the elevation of the slab supports 18 that support the rear ends of the slabs 20. This means comprises two vertically adjustable track bars 44 and 45 positioned adjacent the outer sides of the link belts 17 and operable in slots 46 in the table 12. Each link belt 17 has a plurality of brackets 47 secured thereto and extending outwardly therefrom over the track bars 44 and 45. One of the brackets 47 is provided opposite the end of each cross bar 18. When the track bars 44 and 45 are in their lowermost position they will not elevate the link belts 17 at the location of the slab supports 18 and said link belts will be supported on and move on the table 12. When said track bars 44 and 45 are raised, as shown in Fig. 4, then the link belts at the locations where the slab supports 18 are secured are elevated by the track bars 44 and 45 and the slab supports 18 by which the rear end portions of the slabs 20 are supported are held in an elevated position during that portion of their travel throughout which the slab 20 is being fed to the saw 21. The link belts at the location of the front slab supports 19 rest on the table during this same time. The two track bars 44 and 45 may be connected by a cross bar 48. Also each of said track bars 44 and 45 is provided with two inclined surfaces 49 and 50 positioned near the respective ends of the track bar. The inclined surfaces 49 are slidable on a fixed cross rod 51 and the inclined surfaces 50 are slidable on another fixed cross rod 52. A cross shaft 53

positioned near the intake end of the machine has short lever arms 54 fixedly secured thereto. These short lever arms 54 are connected by pivots 55 with the ends of links 56. The other ends of links 56 are pivotally connected with the cross shaft 48 which connects the two track bars 44 and 45. A hand lever 58 is secured to the shaft 53 at one side of the machine to provide means for rotatively moving the shaft 53. A notched quadrant 59 is provided for the hand lever 58 to engage with whereby the hand lever may be held in any desired position.

An edge view of one of the cedar slabs 20 is shown in Fig. 7, and fragmentary perspective views of the end portions of said slab are shown in Figs. 8 and 9. Cedar slabs of this type are split from cedar blocks or bolts. These slabs are of approximately the same thickness at both ends and both faces thereof are split faces. The grain of the wood is substantially perpendicular to the plane of the slab. These slabs are split with a tool having a flat sharp edge, such as a frow. Where the frow enters the block in splitting the slab the face of the slab immediately adjacent the end will usually be fairly flat and smooth and free from ridges. A flat face portion 60 adjacent the end of a slab is shown in Fig. 9, and is indicated by a tapering out of the dotted line 61 in Fig. 7. At all other locations the face 30 of the slab will be a true split surface with the usual grooves 63 and ridges produced by the grain. Wood from some trees will split with deeper grooves and higher ridges than from others. Also wood from different parts of the same tree may show substantial variation in depth of grooves 63 when split. These slabs are re-sawed to form two tapered shakes from each slab. The line of the cut in re-sawing is indicated by dot and dash line 62 in Figs. 7 and 8. In re-sawing these slabs it is desired to produce shakes that are shin at the tips. However if the saw cut runs into the deeper grooves, such as the grooves 63 in Fig. 8, so as to leave notches in the thinner end of the shake and produce a feathered tip then the shake is rejected as imperfect. It is to avoid having the saw intersect the bottom portions of the deeper grooves 63 that we provide means by which the operator can vertically adjust the rear end of the slab toward or away from the table to provide the correct cut for each individual slab. This variation in the depth of grooves in the face of the slab at the location where the splitting tool entered the slab is usually not enough to require adjustment by the operator to the successive individual slabs. However, in Fig. 6, I have shown a modified form of adjustable cross bar means for supporting the forward end portion of the slab. This cross bar means comprises a cross bar 65 extending between the two link belts 17 and fixedly secured to said link belts and a shake supporting member 66 mounted on the cross bar 65 by means of screws 67 and spacer members 68. By removing the screws 67 and substituting spacer members 68 of different thickness the supporting member 66 may be vertically adjusted and this adjustment will vary the respective thickness of the shake tip and butt formed at the forward end of the slab.

In the operation of this machine an operator stands at the forward end of the machine and feeds the machine by placing the slabs 20 one at a time in the machine with one edge of the slab resting against the guide rail 42, one end of the slab resting in an L shaped slab support 18 and

a smooth forward end portion 60 of each slab resting on a cross bar 19. The slab is thus supported at an incline to the plane of its movement corresponding to the incline at which the saw cut is to be made. As the slab is fed forwardly to the rapidly moving saw said slab is cut into two shakes. If the operator introduces a slab which does not have deep grooves he moves the lever 58 forwardly to lower the slab support 18 which supports the butt end of the slab. This provides a thin tip on the top shake cut from the slab. If the slab has deep face grooves adjacent its rear end, such for instance, as the grooves 63 shown in Fig. 8, then the operator moves the lever 58 rearwardly so as to raise the rear end of the slab enough so that the saw will not intersect the grooves 63 but will emerge from the slab along substantially the dot and dash line 69 of Fig. 8. The link belts 17 at the locations of forward slab supports ride upon the table 12.

The foregoing description and accompanying drawings clearly disclose a preferred embodiment of my invention but it will be understood that this disclosure is merely illustrative and that such changes in the invention may be made as are fairly within the scope and spirit of the following claims.

We claim:

1. A machine for sawing wooden slabs to form from each wooden slab two tapered shakes each having a thicker end portion and a thinner end portion, comprising a horizontal support; a band saw operable horizontally across said support; an adjustable slab conveyor movable horizontally across said support in a direction substantially at right angles to the length of the band saw; slab supporting means carried by said conveyor positioned to support slabs in an inclined position relative to their plane of movement and to advance said slabs to the saw; incline control devices operatively connected with the portion of said slab supporting means that supports the rear ends of the slabs; and slab adjusting means carried by the support in the path of said incline control devices adapted to vary the incline of the slab while the slabs are being cut by the saw.

2. A machine for sawing wooden slabs to form from each wooden slab two tapered shakes each having a thicker end portion and a thinner end portion, comprising a horizontal support; a band saw operable horizontally across said support; belt means movable horizontally across said support in a direction substantially at right angles to the length of the band saw; pairs of transverse slab supports carried by said belt means, each pair of slab supports comprising a support for each end of a slab, the two slab supports of each pair being positioned to support a slab at an incline relative to its plane of movement; and slab support adjusting devices operable to vertically adjust the supports for the rear ends of the slabs while the slabs are being cut by the saw to vary the incline at which the slabs are fed to the saw.

3. A machine for sawing wooden slabs longitudinally and in a plane slightly inclined relative to the medial plane of the slabs to form from each wooden slab two tapered shakes each having a thicker end portion and a thinner end portion, comprising a driven horizontal conveyor embodying two spaced apart endless link belts connected by transverse slab supports; means normally supporting the upper laps of said link belts; conveyor adjusting devices operable to vertically

adjust portions of the upper laps of said link belts that are connected with the rear end portions of said slab supports without adjusting other portions of said upper laps to vary the incline of slabs supported by the slab supports; and a driven band saw positioned with one lap thereof extending across said link belts a short distance above the link belts.

4. A machine for sawing wooden slabs longitudinally and in plane slightly inclined relative to the medial planes of the slabs to form from each slab two tapered shakes each having a thicker end portion and a thinner end portion, comprising endless driven link belt means having a substantially horizontal traveling portion; slab supporting means connected with said link belt means; incline control devices connected with said link belt means at the location of the rear end portion of said slab supporting means; and adjustable slab adjusting devices positioned in the path of said incline control devices and operable to adjust said rear end portions of said slab supporting means to vary the inclination of slabs supported thereby; and a driven band saw extending across said link belt means in the path of slabs carried by said slab supporting means.

5. A machine for sawing wooden slabs longitudinally and in a plane slightly inclined relative to the medial planes of the slabs to form from each slab two tapered shakes each having a thicker end portion and a thinner end portion, comprising a horizontal support; two spaced apart parallel endless link belts positioned with their upper laps on said horizontal support; a driven band saw positioned with one lap thereof extending across said link belts a short distance above the upper laps of the link belts; pairs of transverse slab supports carried by said link belts, each pair of slab supports comprising a support for each end of a slab and each pair of slab supports being positioned to support a slab at an incline relative to its plane of movement; and conveyor adjusting devices operable to vertically adjust the link belts at the location of the supports for the rear ends of the slabs to vary the incline of the slabs relative to their plane of movement.

6. A machine for sawing wooden slabs longitudinally and in a plane slightly inclined relative to the medial planes of the slabs to form from each slab two tapered shakes each having a thicker end portion and a thinner end portion, comprising a horizontal support; two spaced apart parallel endless link belts positioned with their upper laps on said horizontal support; a driven band saw positioned with one lap thereof extending across said link belts a short distance above the upper laps of the link belts; pairs of transverse slab supports carried by said link belts, each pair of slab supports comprising a support for each end of a slab and each pair of slab supports being positioned to support a slab at an incline relative to its plane of movement; vertically adjustable horizontal track members positioned alongside of the upper laps of said link belts; track member adjusting means connected with said track members; and means on said link belts at the locations of the supports for the rear ends of the slabs positioned to engage the track members, whereby the rear ends of the slabs will be vertically adjusted to vary the thickness of the tip portion of one of the shakes made from the slab.

7. A machine for sawing split wooden slabs to produce from each slab two re-sawed tapered shakes and in which each slab has in its faces the usual longitudinal grooves of varying depth re-

sulting from the splitting of the slabs and further has on one face adjacent an end of the slab a substantially smooth surface formed by the entrance of a splitting tool, said machine comprising horizontal endless flexible conveyor means; a driven band saw extending across said conveyor means a short distance above said conveyor means; pairs of transverse slab supports on said conveyor means, the two supports of each pair being spaced apart far enough to receive the front and rear end portion respectively of the slabs and support the slabs in a position inclined relative to its direction of movement, the front support of each pair having a flat surface to receive the smooth surface near the end of the slab and provide a firm support for the forward end of the slab and correctly position the forward end of the slab relative to the saw; and slab support adjusting devices operable to vertically adjust the rear slab support of each pair whereby the width of the tip of a shake formed from the rear end portion of the slab may be adjusted to conform to the depth of the split grooves in the face of the slab.

8. In a machine having a horizontal band saw for sawing wooden slabs longitudinally of the slabs in a plane slightly inclined relative to the medial planes of the slabs to form from each slab two tapered shakes each having a thicker end portion and a thinner end portion, a horizontal conveyor comprising link belt means mov-

able crosswise of the band saw in close proximity thereto; slab supports carried by said link belt means; incline control devices connected with the rear end portions of said slab supports; and readily adjustable slab support adjusting devices positioned in the path of said incline control devices operable to vertically adjust the rear end portions of said slab supports whereby the incline at which the slabs are fed to the saw will be varied.

9. In a machine having a horizontal band saw for sawing wooden slabs longitudinally of the slabs in a plane slightly inclined relative to the medial planes of the slabs to form from each slab two tapered shakes each having a thicker end portion and a thinner end portion, a horizontal conveyor, comprising link belt means movable crosswise of the band saw in close proximity thereto; pairs of transverse slab supports carried by said link belt means, each pair of slab supports comprising a support for each end portion of a slab, the two supports of each pair being positioned to support a slab at an incline relative to its plane of movement; and slab support adjusting devices operable to vertically adjust the supports for the rear end portions of the slabs, whereby the incline at which the slabs are fed to the saw will be varied.

EDWARD E. MARSHALL.
C. B. ZUMWALT.
